(57) **CLAIM**

The ornamental design for an automobile wheel, as shown and described.

DESCRIPTION

FIG. 1 is a right side perspective view of an automobile wheel showing our new design;

FIG. 2 is a front view thereof; and,

FIG. 3 is a left side perspective view.

It will be understood that the broken lines shown in the drawings illustrate portions of the automobile wheel that form no part of claimed design.

1 Claim, 3 Drawing Sheets

FIG. 1

FIG. 2

FIG. 3
